UNITED STATES PATENT OFFICE.

WILLIAM W. ALLEN, OF CINCINNATI, OHIO.

SWITCH-STAND.

No. 883,074.

Specification of Letters Patent. Patented March 24, 1908.

Application filed February 11, 1907. Serial No. 356,804.

To all whom it may concern:

Be it known that I, WILLIAM W. ALLEN, a citizen of the United States, and a resident of Cincinnati, in the county of Hamilton and State of Ohio, have invented a certain new and useful Improvement in Switch-Stands, of which the following is a specification, reference being had to the accompanying drawing, which forms a part thereof.

10 My invention relates more particularly to what are known as "automatically operating" switch-stands, in which means are provided whereby the switch may be thrown by a passing train, but the operating mechanism 15 being constantly held under tension, thus, not only holding the switch in its turned position, but also holding it secure against any attempts to tamper therewith.

The object of the invention is also, to provide a construction wherein as little friction 20 will be had as possible, and permit of its positive action while it is being thrown to its limiting position. At the same time, the construction is such that it may be easily 25 operated by hand by an authorized operator, which, of course, can only be done after the switch has been unlocked.

The purpose of my invention is to provide a switch-stand which will be simple in construction and not easily thrown out of order 30 or affected by the constant more or less rough usage to which the same is subjected.

In the drawings:—Figure 1 is a partly central sectional view, and side elevation; Fig. 2 is a horizontal sectional view taken on the 35 lines 2—2 of Fig. 1; Fig. 3 is a detail view of the tension applying mechanism whereby tension is applied to the operating shaft or mechanism; and Fig. 4 is a similar view to 40 Fig. 1, with a part of the upper portion broken away, and showing a modified form of my invention.

Like letters of reference indicate identical parts in the respective figures.

45 The switch stand comprises a base or casing A, having an opening in its top which is provided with a collar B, through which the operating shaft or target spindle C takes. The shaft or spindle C is preferably made 50 square at its upper end, as shown, while the lower end within the casing or base A may be slightly larger and is made round as shown in the drawings. The collar B is provided with a square recess to receive the square end 55 of the sliding block D. The sliding block D is mounted on the sleeve E, which is also

squared, so that the sliding-block D will turn with it; the sleeve E is provided with a square opening for the reception of the vertical shaft or spindle C, so that any movement or turn of the sleeve E will compel the shaft or spindle C to move with it. The block D is loosely mounted on sleeve E, to permit it to slide thereon.

60 F represents an operating handle, which is pivoted to the sleeve E in any suitable manner, and is connected with the sliding block D by the lifting strap G. It will thus be seen that when the handle F is either lifted or turned downwardly, that block D must necessarily move in a similar direction by reason of the lifting-strap G, which has pivotal connection with both the handle and block.

65 The construction thus far described is that of a well-known style of switch-stand now in use.

70 Loosely mounted on the vertical shaft or target spindle C is a block H which is preferably formed as can more clearly be seen in Fig. 2, with rounded corners and concaved sides, so as to provide definite bearing surfaces, whereby the vertical shaft may be given limiting positions. This block H is also made integral with the lower end of 75 collar B. Pivoted secured within the base or casing A, at the point a, is the bell-crank-lever J, the lower end of which is preferably bifurcated, as at b, b, so as to take about the lower end of the vertical shaft or spindle C, 80 as shown in Fig. 1, and in dotted lines, in Fig. 2. In order to reinforce the bell-crank-lever J, I prefer to provide the webs c, as shown. The bifurcations b, of the bell-crank-lever provide resting or bearing points 85 for the spring K, which surrounds the lower end of the vertical shaft, while the upper end of the spring bears either against the block H, or if desired, a washer may be placed intermediate of the upper end of the spring and 90 the block H. The sleeve E takes into the square recess in collar B, and butts against it, thereby securely holding collar B down onto casing A, against the action of the spring K, when block D is raised with the handle F. 95 The upper end of the bell-crank-lever terminates in a spindle or journal d on which is rotatably mounted the roller L. This roller is held in place by a pin e, or in any other suitable manner. It is apparent from this construction that the spring K tends to depress 100 the lower end of the bell-crank-lever J,

105

110

pressing the roller at the upper end of the bell-crank-lever against the block H, thus exerting a constant tension and preventing the free action of the block H, with the vertical shaft or spindle C, when the parts are locked in place.

- 5 In order to lock the operating handle F in its normal position, and prevent any tampering with the switch, the sliding block D may 10 be provided with the lug M, extending upwardly, which may take through an opening in or between the bifurcated ends of the handle F, and receive a lock or other device through the opening in the lug.
- 15 The operation of the construction is as follows:—When it is desired to throw the switch to any desired position by hand, the handle F is unlocked from the lug M, and raised, which draws up the lifting strap G, 20 whereby the sliding block D will be withdrawn from the square recess in collar B, when the handle may be swung around, and with it the vertical shaft C (which is connected to the switch tongue by the usual 25 crank O at its bottom), which turns in this condition without moving the block and the integrally formed collar, thus leaving the roller L in contact with the same concaved side as before. When the switch is to be 30 thrown automatically, however, then of course the handle F, remains locked to block D, and the train exerting sufficient pressure to overcome the tension of spring K, throws or turns the vertical shaft or target spindle 35 C, and with it the sleeve E, block D and collar B, with the integrally formed block H, compelling the roller L on the bell-crank-lever to ride around the corner of block H, into another concaved side thereof, thus 40 holding the entire mechanism in its next limiting position. By reason of the bell-crank-lever having the pivotal connection at a, it is apparent that the roller L may ride around the rounded corners of the block H.
- 45 In Fig. 4 I have shown a slight modification of the construction just described, in that I provide a different bearing surface for the upper end of the spring K, and the block H with the collar B is shown above and to 50 the outside of the base or casing A. This collar is of course provided with the squared opening as previously set forth with reference to the collar B, into which the squared end of the sliding block D takes and also the 55 end of sleeve E, which latter bears against the collar. With this construction it will be seen that the frictional contact of spring K with the block H as shown in Fig. 1, is obviated, and the possibility for wear thus 60 minimized, as the upper end of the spring K, which does not turn, will not have the rubbing contact with the block H when the latter is revolved during the automatic operation of the switch. In this construction 65 of course the upper end of the bell-crank-

lever J must extend through an opening in the top of the casing or base A, as indicated, so as to permit the roller L to contact with and bear against the block H. The base or casing A may be made in any convenient 70 form, and I have illustrated it for example as comprising two parts, the one being bolted onto the other, so that ready access may be had to its interior.

I have shown and described what I believe 75 to be the simplest constructions of my improvement, but the same may be modified in slight minor details without departing from the spirit of my invention, and I do not wish to be understood as limiting myself to the 80 exact constructions shown and described, but

What I claim as my invention, and wish to secure by Letters Patent, is:—

1. In a switch stand, a base or casing, a rotatable shaft mounted therein, means pivotally mounted at its one end while the other or free end is adapted to act on said shaft, and mechanism having controlling connection with said means whereby the rotation of the shaft is affected.

2. A switch-stand comprising a base or casing, a rotatable shaft taking there-through, said base or casing being provided with a collar which forms one member of a lock or clutch, a second member slidably mounted 90 on the shaft and adapted to take into said first member, whereby the shaft is locked against rotation independently of the lock or clutch, and a block loosely mounted on said shaft, in combination with means pivotally mounted within the base or casing, and a spring acting on said pivoted means whereby the rotation of the shaft is affected when both members of the clutch are in their normal position.

3. A switch stand comprising a rotatable shaft, means pivotally mounted adjacent to said shaft and adapted to swing in the arc of a circle, and a spring exerting its tension on said means, compelling it to move through 105 the arc of a circle and act on said shaft at right angles to its axis, thereby affecting the rotation of said shaft when automatically operated.

4. A switch-stand comprising a rotatable 110 shaft, a block loosely mounted thereon, pivoted means adjacent to said shaft, one end of said means adapted to contact with and bear against said block, and a spring arranged to exert tension on the other end of 120 said pivoted means whereby said means is made to bear against said shaft to affect its rotation when automatically operated.

5. A switch-stand comprising a rotatable 125 shaft, means pivoted adjacent to said shaft and having its one end bifurcated and extending about said shaft, while its other end is adapted to bear against the shaft, and a spring bearing on the bifurcated end of said pivoted means whereby the other end affects 130

the rotation of the shaft when the same is operated automatically.

6. A switch-stand comprising a rotatable shaft, a bell-crank-lever pivoted adjacent to said shaft, and a spring bearing on one end of said lever, whereby the other end affects the rotation of said shaft.

7. A switch stand comprising a base or casing, a rotatable shaft taking through said casing and having its bearings therein, means pivoted in said casing so as to swing in the arc of a circle, and mechanism within the casing acting on said means whereby the latter is made to move through the arc of a

circle and held in frictional contact with the 15 shaft to affect its rotation when automatically operated.

8. A switch-stand comprising a base or casing, a rotatable shaft mounted in said casing, a bell-crank-lever mounted within 20 said casing and adjacent to said shaft, and mechanism acting on one end of said lever whereby the other end is made to exert pressure on said shaft and affect its rotation.
